[57] CLAIM

The ornamental design for an information display device for motor vehicle interior, as shown and described.

DESCRIPTION

FIG. 1 is a perspective view taken from the top, left,

and frontal directions of a first embodiment of my new design for information display device for motor vehicle interior;

FIG. 2 is a front elevational view of the first embodiment;

FIG. 3 is a left side elevational view of the first embodiment;

FIG. 4 is a right side elevational view of the first embodiment;

FIG. 5 is a perspective view taken from the top, the left, and the frontal directions of a second embodiment of my new design for information display device for motor vehicle interior;

FIG. 6 is a frontal elevational view of the second embodiment;

FIG. 7 is a left side elevational view of the second embodiment;

FIG. 8 is a rightward side elevational view of the second embodiment;

FIG. 9 is a top plan view of the first and second embodiments of my new design for information display device for motor vehicle interior;

FIG. 10 is a bottom plan view of the first and second embodiments;

FIG. 11 is a rearward elevational view of the first and of the second embodiments;

FIG. 12 is a sectional elevational view taken along lines 12—12 of FIGS. 2, 6, and 9; and

FIG. 13 is a sectional elevational view taken along lines 13—13 of FIGS. 2, 6, and 9.

FIG. 5FIG. 1FIG. 6FIG. 7FIG. 8FIG. 12FIG. 13

FIG. 212 ← → 13

12 ← → 13

FIG. 10FIG. 4FIG. 3FIG. 11
